ATTORNEY.

UNITED STATES PATENT OFFICE.

WILLIAM McCABE, OF PITTSBURG, PENNSYLVANIA.

COUNTER-BALANCE FOR HINGED COVERS.

SPECIFICATION forming part of Letters Patent No. 461,485, dated October 20, 1891.

Application filed February 6, 1891. Serial No. 380,534. (No model.)

To all whom it may concern:

Be it known that I, WILLIAM McCABE, a citizen of the United States, residing at Pittsburgh, in the county of Allegheny and State of Pennsylvania, have invented certain new and useful Improvements in Counter-Balances for Hinged Covers and Doors; and I do hereby declare the following to be a full, clear, and exact description of the invention, such as will 5 enable others skilled in the art to which it pertains to make and use the same, reference being had to the accompanying drawings, which form a part of this specification.

My invention relates to an improved counter-balance for doors, lids, &c.; and it consists 15 in certain details of construction and combination of parts, as will be fully set forth hereinafter.

In the accompanying drawings, Figure 1 is 20 an end sectional elevation of a box or case having a vertically-swinging hinged lid or cover and provided with my improved counter-balance. Fig. 2 is a plan view of a portion of the same.

To provide a vertically-moving lid or cover 25 *a* with my improved balance, I attach to the side of the box *b*, by means of a suitable connection *c*, a short bar *d*, which is connected at its outer extremity to another *e*, which in 30 its turn is pivoted to the lid or cover *a*. Pivots attached to the two connected extremities of these bars *d e* is a short coupling *f*, to which a spiral spring *g* is connected. The other end of this spring *g* is attached rig-

idly to the rear wall of the box *b* by means of 35 a screw-eyelet. Formed in at the pivots of the two bars *d e* is a stop *k*, of ordinary construction, which will permit the said bars *d e* to move about their pivotal point until the same are almost in line with the other. 40

In operation, when the lid *a* is raised the two bars *d e* commence to separate, and the tension being on the spring *g* the same in closing materially aids the movement of the door *a* upward, and the said lid or door will 45 remain in that position until drawn downward by pressure.

Having thus described my invention, I claim—

The combination, with a box and its hinged 50 lid, of the two bars pivoted, respectively, at one end to the lid and to the box, and the meeting ends of said bars being pivotally connected to each other, a coupling-bar connected at one end to the pivot connecting said bars 55 and projecting laterally from the bars, and a coiled spring extending from the other end of said coupling-bar and fastened directly to the rear wall of the box, substantially as described, for the purpose specified. 60

In testimony that I claim the foregoing I hereunto affix my signature this 15th day of December, A. D. 1890.

WILLIAM McCABE. [L. S.]

In presence of—

A. A. HEINER,
O. D. LEVIS.
